His Attorneys.

Patented Oct. 12, 1926.

UNITED STATES PATENT OFFICE.

FRED B. HAMBLIN, OF ST. LOUIS, MISSOURI.

COLLAPSIBLE AND ADJUSTABLE SHELVES.

Application filed December 7, 1925. Serial No. 73,942.

This invention relates to improvements in collapsible and adjustable shelves.

An object of the invention is to provide a structure that may be folded flat to facilitate the packing thereof and which may be readily set up to form a series of horizontal compartments with means for adjusting the structure so that it can be conveniently hung against a flat wall or against either a right or left angle of a wall.

Another object of the invention is to provide a convenient portable shelf structure suitable for use as a shoe cabinet or a storage or display container for other articles.

Additional advantages of the structure will be apparent from the following detailed description thereof, taken in connection with the accompanying drawing in which

Fig. 1 is a perspective view showing the device set up; and

Fig. 2 is a view showing the manner in which the device is collapsed or folded.

In the embodiment of the invention, the device is shown as including a pair of side walls 1 and 2. The wall 2 is somewhat longer than the wall 1, forming an upper extension 3. Arranged transversely between the walls 1 and 2 are a series of horizontal walls 4 arranged in vertical spaced relationship and connected with the side walls by double hinges 5 so that the side walls may be folded one against the other with the walls 4 therebetween, in the manner clearly illustrated in Fig. 2 of the drawing.

While it is not intended to limit the material from which the device may be made, it is preferable to make it of relatively thick paper board with the hinges of strong fabric adhered to the adjacent edges of the members 4 with the side wall. This framework may be covered if desired with cloth, such as cretonne, to give it a finished appearance.

The extension 3 of the wall 2 is provided with perforations 6 through which supports, such for instance as nails, may be projected to support the device against the wall of a room or other support, such as a cabinet or the like.

A back member, comprising a wall 7 and a pair of wings 8, said wings 8 being hinged to the back member 7 by fabric straps 9, is arranged to be removably connected with the walls 1 and 2. The length of the back member is that of the wall 2 including the ex-

tension 3, so that when the back member is in position, there will be a marginal flange forming a wall partially around the upper face of the upper end of the shelves 4. The back member is also provided with a perforation 10 by means of which it may be hung upon a support mounted in a wall at an angle to the wall carrying the supports projecting through the openings 6 in the side wall.

The back member is arranged so that it may be removably connected with the side walls by providing snap connections, preferably in the form of glove fasteners, and including a socket member 11 connected into the side walls and a ball member 12 carried by the wings 8 of the back member.

The snap devices are preferably disposed as shown in the drawings, namely, with two spaced ball members carried by each wing 8 and four spaced socket members mounted in each of the side walls 1 and 2 at equally spaced distances from the corners of the walls. It is thus possible to adjust the back member on either one of the members 4 so that the device may be mounted in a right or left angle of a room wall.

The back member serves to reinforce and support the shelf structure in horizontal adjustment and by disconnecting the back member from the wall 1, the wall 1 may be pressed inwardly toward the wall 2 and folded thereagainst with the shelf members 4 disposed therebetween and the back member connected with the wall 2 may then be folded over the wall 1. This provides for conveniently adjusting the device so that it may be packed in a flat condition for transportation.

The device is particularly adapted for use as a portable shelf structure, because it is readily adjustable and may be conveniently mounted. While it has a wide range of use, it is particularly useful as a shoe cabinet for traveling purposes.

I am aware that the invention may be modified in certain particulars without departing from the spirit and scope thereof.

What I claim and desire to secure by Letters Patent is:—

1. A device of the class described comprising vertical side members, a plurality of transversely extending spaced walls having hinged connection along the adjacent edge thereof with the side members, a continuous back adapted to close the back area

releasably connected with the side member arranged to hold the device in extended adjustment when connected with said side member and to permit the device to be collapsed when released so that the side members and back wall may be folded flat against each other with the transverse members interposed between the side members.

2. A device of the class described comprising side members, one of which is extended upwardly beyond the top edge of the other forming an extension, said extension being provided with means for connecting the device with a support in a vertical plane, a back member comprising a wall and hinged wings connected with the wall, disengageable connecting members between the wings and opposite ends of said side members, and a plurality of spaced walls having hinged connection with the side walls.

3. A device of the class described comprising side members, one of which is extended upwardly beyond the top edge of the other forming an extension, said extension being provided with means for connecting the device with a support in a vertical plane, a back member comprising a wall and hinged wings connected with the wall, disengageable connecting members between the wings and opposite ends of said side members, and a plurality of spaced walls having hinged connection with the side walls, said back member extending to the plane of the upper edge of the longer one of said side members, and said back member being provided with means for connecting it with a support in a vertical plane at an angle to the plane supporting the side member.

4. A device of the class described comprising side walls, a plurality of transversely extending walls, double-hinge strips connecting said transverse walls with said side walls, and permitting one side wall

to be folded against the other with the transverse walls between, an end member, 45 wing members hinged to said end member, and a plurality of fastening devices, one member of which is carried by said wings and the other member of which is carried by said walls, whereby said end member 50 may be releasably connected with opposite ends of said side walls.

5. A device of the class described comprising side walls, a plurality of transversely extending walls, double-hinge strips 55 connecting said transverse walls with said side walls, and permitting one side wall to be folded against the other with the transverse walls between, an end member, wing members hinged to said end member, a plurality of fastening devices, one member of which is carried by said wings and the other member of which is carried by said walls, whereby said end member may be releasably connected with opposite ends of said side 60 walls and means for connecting one of said side walls and said back member with supports in a vertical plane and at right angles to each other.

6. A device of the class described comprising continuous side walls, a plurality of transversely extending walls, hinged connections between the transverse walls and said side walls and permitting one of said walls to be folded against the other with 75 the transverse walls therebetween, a continuous back wall adapted to close the back area, a releasable connection between the side walls and the back wall arranged so that when connected the device will be held in 80 extended position and when released the device may be collapsed, and the back, side and transverse walls folded in flat relationship.

FRED B. HAMBLIN.
